UNITED STATES PATENT OFFICE.

LEWIS P. HALLADAY, OF STREATOR, ILLINOIS.

GO-CART.

No. 822,944.

Specification of Letters Patent.

Patented June 12, 1906.

Application filed July 27, 1905. Serial No. 271,429.

To all whom it may concern.

Be it known that I, LEWIS P. HALLADAY, a citizen of the United States, residing at Streator, in the county of LaSalle and State 5 of Illinois, have invented a certain new and useful Improvement in Go-Carts, of which the following is a specification.

My invention relates to go-carts, and has for its object to provide new and improved 10 constructions in devices of that character.

The invention is illustrated in the accompanying drawings, wherein—

Figure 1 is a side elevation; Fig. 2, a sectional view on line 2 2 of Fig. 1; Fig. 3, a sectional view on line 3 3 of Fig. 1; Fig. 4, a detail sectional plan of one of the arm-rests, taken on line 4 4 of Fig. 1; and Fig. 5, a detail sectional view on line 5 5 of Fig. 1.

Like letters of reference indicate like parts 20 in all the drawings.

My invention comprises certain improved constructions and devices in baby-carriages or go-carts relating, among other things, to the general construction of such devices and 25 to arrangements whereby the parts are collapsible, so as to form when folded a relatively compact parcel which may be easily transported. The construction of the device also provides for adjusting the supporting parts—such as the seat, back, and foot-rest—at various angles, so that the child may sit upright or recline in any position desired.

Another object of the invention is to provide a very simple construction.

As will appear by the following description, the supporting-framework may be made to consist entirely of relatively thin strips of metal so arranged and coördinated as to brace each other when the device is in use in 40 its various positions and to be folded up into a convenient shape when not in use.

I will first describe the parts as they are related when the device is in readiness for use—that is, as they are shown in the full outline 45 in the figures—and will later refer to the various positions which these parts may take, certain of which are shown by the dotted lines in Fig. 1. The main framework of the go-cart consists generally of two obliquely-50 arranged frames pivoted to each other at approximately their central points, one of them carrying the forward-wheel axle and giving support to the back portions of the seat and its associated parts, the other carrying the 55 rear-wheel axle and supporting the forward portions of the devices making up the seat.

The first-mentioned frame consists, preferably, of two long thin strips of metal A A, connected at the top by a hand-grip A' of any desired description, further down by the 60 cross-rod A², and being curved or offset, as shown at A³.

The seat-back (designated generally by the letter B) is formed, preferably, of a continuous strip of metal B', bent into the form of a 65 three-sided rectangle and having on its rear edges the pairs of notches B² B². The framework thus formed is filled in any desired manner so as to form a back for the seat—as, for example, by the padded board B³—which 70 may be secured into the framework by the screws B⁴ B⁴. The back is pivoted to the offset parts A³ A³ of the strips A A in any desired manner—as, for example, by the rivets B⁵ B⁵. In making pivotal connections be- 75

tween the various parts of my machine I prefer to use rivets, as shown, although, of course, the parts might be secured together in any other suitable manner. The upper end of the seat-back B is held in its upright 80 position by means of a clip B⁶, slotted at B⁷ B⁷ for the set-screws B⁸ B⁸ and comprising a hook B⁹, extending over the cross-rod A². It will be understood that the back is a trifle narrower than the frame formed by the strips 85 A A, so that when it is turned back to its reclining positions it will easily clear such strips. In order that the back should be supported in various positions other than its upright position, I provide a back-support 90 (designated generally by the letter C) comprising strips of metal C' C', pivoted to the strips A A at C² C², and connected at their lower ends by the cross-rod C³, thus forming a rectangular framework lying inside the 95 strips A A when the back is in its upright position.

The back may be disengaged from the cross-rod A² by loosening the set-screws and pushing up the clip B⁶, and it may then be 100 swung back through the supporting-frame formed by the strips A A, the framework formed by the side strips C' C' being pulled out sufficiently to hold the back at the proper angle. The notches B² E² will assist in keeping the back in the desired position. The back and its support in a reclining position are shown by the dotted lines in Fig. 2, the position of these parts being designated, respectively, by the letters B^X C^X. 105

The device is preferably provided with arms, one at each side, composed of strips of

metal D D, pivoted to the parts A A at D' D', and arm-rests D² D², secured to the strips D D by the screws D³ D³. On the strips D D are the lugs D⁴ D⁴, and pivoted to these lugs are the links D⁵ D⁵, which connect the arms with the other part of the main supporting-frame of the device. This framework consists of two strips of metal E E, pivoted to the strip A A at E' E' and to the links D⁵ D⁵ at E² E² and at their other ends carrying the rear-wheel axle.

The seat may be made in any desired form. I have here shown two angle-iron strips F F, supporting the seat part F', which may be a padded board and which is secured thereto by the screws F² F². The seat at the back has a pivotal connection with the framework by the same rivets E' E' which serve to secure together the two sections of the frame. Links G G connect the arm-strips D D with the seat angle-irons F F, the latter joint being made by means of a rod G' passing through forward extensions of such angle-irons.

I prefer to provide the device with a foot-rest which I will designate generally by the letter H, the position of which is preferably changed when the back is in its inclined position. This foot-rest comprises two strips H' H', pivoted on the rod G', curved at their upper ends to the extent of the width of the links G G and having the offsets H² H², forming shoulders to abut against the links G G to limit the inward movement of the lower end of the foot-rest. At the lower end of these supporting-strips is the footboard H³, having brackets H⁴ H⁴, pivoted at H⁵ H⁵ to the strips H' H'. The strips H' H' are preferably of somewhat lighter material than the rest of the framework and are elastic enough, so that when the foot-rest is moved to its horizontal position the offsets may be pushed past and under the seat. This position of the foot-rest is shown by the dotted lines designated generally by the letter H^X in Fig. 1. The footboard need not, of course, be folded over as it is shown in this figure.

The device is preferably mounted on rubber-tired wire wheels J, and these may be of any ordinary type. The front wheels I have shown as mounted on an axle K, which is carried at the end of the frame-pieces A A, and these I prefer to make with the lateral hooks or offsets K' K', so that the axle may get a double bearing at each end. The rear wheels I mount in a somewhat similar manner on the axle L, carried by the strips E E. In the case of the back wheels I may provide an elastic mounting comprising links L' L', pivoted to the strips E E at one end and supplying a bearing for the axle L at the other. Between the links L' L' and the curved ends L² L² of the strips E E, I interpose the coiled springs L³ L³. This arrangement, however, is not essential to my invention,

tion, and any other form of mounting for the wheel-axle may be utilized.

I have thus described in detail my invention in one of its embodiments; but it is clear that there might be considerable change made in details of construction and material without going beyond the scope of my invention, and therefore I do not wish to limit myself to all of the forms, devices, and constructions shown and described.

The use and operation of my improved go-cart will perhaps have been made sufficiently clear by the foregoing description of its parts.

When the device is opened out, it will be seen that the parts are so related to each other as to form a sort of trusswork which divides up the strain. To collapse the device when it is not in use, it is only necessary to grasp the handle A' and one of the arm-rests D², and all the parts will give on their pivots, so as to be brought together into a very compact form. The positions which the parts take when collapsed are shown by dotted lines in Fig. 1. In order to avoid confusion, the folding of the device has been illustrated as being brought about by maintaining the strips A A in their normal position and rotating the strips E E, and consequently the imaginary ground-line has been inclined to the position indicated by the line X Y. The weight on the seat when the device is opened out will keep the parts in proper position, no change being effected by pushing on the handle A, since this is connected with a part of the frame which supports the forward wheels. It will be observed that the frames made by the strips A A and E E are connected by two pairs of members, the links D⁵ D⁵ and the arms D D, which are substantially parallel when the supporting-frames are spread—that is, when the device is in use. This serves to lock the framework in its open position, so that it requires a direct upward pull to collapse the device. This makes it impossible that the go-cart should be folded up from any jar incident to its use.

I claim—

1. In a collapsible go-cart, the combination of a supporting-framework comprising two substantially centrally pivoted hollow frames adapted to be drawn together when the device is collapsed, with a seat, a back, said back pivoted to the framework at its lower end, and a clip to secure the upper end of the back to the framework.

2. In a collapsible go-cart, the combination of a supporting-framework comprising two substantially centrally pivoted hollow frames adapted to be drawn together when the device is collapsed, with a seat and a back, said back pivoted to the framework at its lower end so as to be swung backwardly, a rod against which the back lies in its various inclined positions, and links connecting the rod with one of said frames.

3. In a collapsible go-cart, the combination of a supporting-framework comprising two substantially centrally pivoted hollow frames adapted to be drawn together when the device is collapsed, with a seat, a back, a foot-rest having a substantially upright and a horizontal position, and a spring-latch to hold the same in either position.
4. In a collapsible go-cart, the combination of a supporting-framework comprising two substantially centrally pivoted hollow frames adapted to be drawn together when the device is collapsed, with a seat, arm-rests, a foot-rest, and links connecting the seat and arm-rests pivoted to the seat having an extension with a spring-latch to engage the said links on the seat.
5. In a collapsible go-cart, the combination of a collapsible framework, with a seat and a pivoted foot-rest comprising an extension having a spring-latch adapted to engage part of the go-cart so as to hold the foot-rest in substantially vertical or horizontal position.
- 25 6. In a collapsible go-cart, the combination of a framework comprising two centrally-pivoted frames, and means for locking such frames in their open positions, such means comprising pivoted connecting parts lying substantially parallel when the device is in its open position.
7. In a collapsible go-cart, the combination of a framework comprising two centrally-pivoted frames with arms pivoted to one of such frames, and a link pivoted to the other and to such arm, and lying substantially parallel with such arm.
8. In a collapsible go-cart, the combination of two pivoted frames with arms pivoted to one of such frames, links connecting the other frame with said arms, said links lying under and along the arms.
9. In a collapsible go-cart, the combination of two pivoted frames with arms pivoted to one of such frames, links connecting the other frame with said arms, said links lying under and along the arms, a seat pivoted to the frames, and links from the arms to the seat.
10. In a collapsible go-cart, the combination of a framework comprising two centrally-pivoted frames, a seat pivoted to such frames at the back, pivoted arm-rests, a link connecting the forward part of the seat with such arms, a foot-rest pivoted to the forward part of such seat, and having an upwardly-extending member lying along and engaging with such link when the foot-rest is in its substantially vertical position.
11. In a collapsible go-cart, the combination of a framework comprising two centrally-pivoted frames, a seat pivoted to such frames at the back, pivoted arm-rests, a link connecting the forward part of the seat with such arms, a foot-rest pivoted to the forward part of such seat, and having an upwardly-extending member to engage with such link, such member of elastic material and adapted to engage with the seat when the foot-rest is in its horizontal position.

LEWIS P. HALLADAY.
